CAN OPENER

Filed Dec. 6, 1926

INVENTOR:

MATSUTARO UYEHARA.

By His Atty:

Edward G. Kojing

UNITED STATES PATENT OFFICE

MATSUTARO UYEHARA, OF LOS ANGELES, CALIFORNIA

CAN OPENER

Application filed December 6, 1926. Serial No. 152,897.

This invention relates to can-openers, and its object are to provide an implement of this character having improved means for positioning the blade relative to the can-rim to make the cut adjacent thereto, although the fulcrum prong of the can-opener may be eccentrically positioned relative to the rim.

In ordinary can-openers, it is of common occurrence that the fulcrum prong is not accurately centered when a cut is about to be made. The blade subsequently will run out and prevent movement of the can-opener. To avoid this objection, I have provided a guide member integral with the cutting blade, and having thereon a roller adapted to roll upon the outer surface of or along the rim of the can, to thereby retain the blade in its proper cutting position.

Another object is to proportion the parts so that the blade will follow the contour of the rim although the can may be of oval, square, round, or irregular form.

Other objects and advantages may appear in the subjoined detail description.

In the drawings, Figure 1 is a plan view of a can-opener embodying the features of my invention. Fig. 2 is a side view of the same. Fig. 3 is a detail view of the guide member and roller. Fig. 4 is a side view of the guide member and roller having one part of the guide member cut away. Fig. 5 is a perspective view of the guide member with the roller removed therefrom. Fig. 6 is a fragmentary and sectional view of a can, showing the can-opener in position for cutting the top of the can. Fig. 7 is a plan view of a blank before bending to form the guide member.

Referring in detail to the drawings, my improved device consists of a bar 11, having an off-set prong 12, provided with a sharp-pointed extremity 13, and on its opposite extremity, a handle 14. On bar 11, there is mounted a guide member 15, having an integral blade 16, the integral arms 17 and 18, a top 19, adapted to slide upon the top of bar 11, and a neck portion 20, of oval section extending in slot 21, in bar 11. The neck portion 20, allows a limited swivel movement of the guide member in the cutting

operation, and thereby permitting the guide member to follow any regular or irregular rim of a can, and allows the implement to turn an angular corner of a rectangular can or square can.

The top 19 and neck portion 20, are fixed to the body portion of the guide member. A bearing pin 22, extends through the top and through the extremities of arms 18 and 17. A roller 23, is mounted on the bearing pin 22, and projects from the housing formed by said arms, and is adapted to roll upon the rim of the can to be cut, serving to maintain the blade in a suitable spaced relation to the rim of the can. The roller further insures that the can-opener will operate easily. The blade and guide member, being slid able, is therefore adjustable to the size of the can, and will readily follow the contour of the rim of the can.

In use, the top of the can to be opened, is first punched with an initial incision approximately at the center of the top. The prong 12 is then inserted in this initial cut, and serves as a fulcrum for the bar and handle. The blade is then positioned adjacent to the rim of the can, with the roller in engagement with the side of the can or with the rim thereof, as shown in Fig. 6. A pressure on the handle will cause the blade to pierce the can-top. The can is then rotated until the desired cut is made. Obviously, the can may be held stationary and the handle of the opener actuated to perform the cutting operation. With the roller riding upon the rim of the can, the blade is maintained a certain distance from the rim, whether the prong was perfectly centered or not, thereby attaining ease of operation in opening the can.

The swivel movement of the guide, together with the action of the roller, adapts the device to various sizes and forms of cans and to irregular surfaces.

It will be observed that the device is positive in action, and the roller reduces friction in operation so as to render necessary only a minimum exertion on the part of the operator, the device also possessing the characteristics of simplicity, durability and effi-

ciency in construction and operation, and consisting of but few parts easily and cheaply manufactured and assembled.

What is claimed is:

1. In a can-opener having a slotted bar, a guide member slidable relative to said bar, a neck portion on said guide member extending in said slot, said neck portion being narrower than the slot, a retaining top portion integral with the neck portion, and engaging with the top of the bar, a blade integral with and depending from the guide member, other portions of the guide member extending to form a protecting and supporting roller cage, and a roller mounted in the guide member and projecting from the protecting and supporting cage in opposed relation to the blade and spaced apart from the blade.
2. In a can-opener, the combination with a slotted bar, of a guide member slidable relative to said bar, a neck portion on said guide member extending in the slot in the bar, said neck portion having an oval contour, a retaining top portion integral with the neck portion, and engaging with the top of the bar, a blade integral with and depending from the guide member, other portions of the guide member extending to form a protecting and supporting roller cage, and a roller mounted in the guide member and projecting from the protecting and supporting roller cage in opposed relation to the blade, the roller being spaced apart from the blade.
- 35 In testimony whereof, I hereunto affix my signature.
